UNITED STATES PATENT OFFICE.

GEORGE PARKER HOLDEN, OF KINGSTON, NEW YORK.

DESIGN FOR A BICYCLE-SADDLE SPRING.

SPECIFICATION forming part of Design No. 31,006, dated June 13, 1899.

Application filed May 25, 1898. Serial No. 681,730. Term of patent 7 years.

To all whom it may concern:

Be it known that I, GEORGE PARKER HOLDEN, a citizen of the United States, residing at Kingston, in the county of Ulster and State 5 of New York, have invented and produced a new and original Design for Bicycle-Saddle Springs, of which the following is a specification, reference being had to the accompanying drawings, forming a part thereof.

Figure 1 is a plan view of a bicycle-saddle spring, showing my new design; and Fig. 2 is a section on the line xx and elevation of half of the saddle-spring.

As shown in the drawings, the leading features of this design for a wire bicycle-saddle spring consist in the upwardly-curved back portion and the parallel pommel-loops, each having a double curve and outwardly and upwardly facing end, the inner members of 15 said pommel-loops being bent double at their rear parts and continued forward as a base-loop, the outer members of the pommel-loops being continued outwardly, upwardly, and around to the rear part of the spring, where

they form the end portions thereof, and parallel or side by side run down to connect with the rear of the base-loop. The configurations at opposite sides of the central vertical plane are similar, but reversed. 25

A A' is the upwardly-curved back portion, 30 and B B' are the parallel pommel-loops, each having a double curve and outwardly and upwardly facing end and whose inner members C C' are bent double at D D' and continued forward as a base-loop F, the outer 35 members E E' being continued outwardly, upwardly, and around to the rear, where they form the end portions G G', and parallel and side by side run down to connect at D D' with the back of the base-loop F. 40

What I claim is—

The design for a bicycle-saddle spring substantially as shown and described.

GEO. PARKER HOLDEN.
